UNITED STATES PATENT OFFICE.

CHARLES S. KLINE, OF DENVER, COLORADO, ASSIGNOR TO ECONOMY PATENT MANUFACTURING COMPANY, OF DENVER, COLORADO, A CORPORATION OF COLORADO.

GAS-ENRICHING MACHINE.

SPECIFICATION forming part of Letters Patent No. 783,790, dated February 28, 1905.

Application filed November 25, 1904. Serial No. 234,266.

To all whom it may concern:

Be it known that I, CHARLES S. KLINE, of Denver, in the county of Denver and State of Colorado, have invented certain new and useful 5 Improvements in Gas-Enriching Machines, of which the following is a specification.

My invention relates to machines for mixing hydrocarbon vapor and air or ordinary illuminating-gas; and it has for its object the 10 construction of a machine that will most effectively mix said products to produce an enriched gas or carbureted air for consumption that will be reasonable in cost of manufacture.

The special object of my invention is to enrich the ordinary illuminating-gas in use in 15 large cities, so that the expense of light and heat therefrom will be materially reduced.

The construction and advantages of my invention will be explained at length hereinaf- 20 ter and illustrated in the accompanying drawings, in which—

Figure 1 is a view in elevation of my invention; Fig. 2, a horizontal sectional view thereof; Fig. 3, a vertical sectional view on the line 25 xx of Fig. 2; Fig. 4, a detail view of the packing used for distributing the hydrocarbon vapor; Fig. 5, an enlarged view in section of the filling-cup, and Figs. 6 and 7 vertical sectional views showing modifications of the ar- 30 rangement of the mixing-partitions.

In the drawings similar reference characters refer to corresponding parts throughout the several views.

My invention consists of a sheet-metal tank 35 A, made of any desired shape and size, the shape selected for illustration in the drawings, however, being cylindrical, supported by suitable legs or feet a . The inner and outer surfaces of the tank are covered with a coat- 40 ing of tar to prevent freezing and the condensation of water on the exterior of the machine. The tank is divided into two compartments by a partition B, the smaller compartment, C, being again divided by a horizontal partition c 45 and is used for the storage-tank for hydrocarbon, while the larger compartment, D, is used as the mixing-chamber and is provided with a number of vertical partitions E. Said par-

titions E are fastened alternately to the opposite sides of the tank and have their free ends 50 extending to within a short distance of the side of the tank opposite to that to which it is secured, so as to make the passage-ways between said partitions staggered, as shown in Fig. 2. The partitions E are also secured to 55 the top of the tank, but do not reach quite to its bottom, leaving a space for the distribution of liquid hydrocarbon therethrough.

F represents a pipe for the admission of air, illuminating-gas, &c., and G the pipe for supplying the product of the machine to the burners.

The spaces between the partitions E are filled by strips of redwood-bark H next to said partitions and the spaces between the strips of redwood-bark are filled with pieces of sponge I and pieces or strips of vegetable fiber, such as loof J, sometimes called "luffa." The purpose of the redwood-bark is to carry the liquid hydrocarbon upward by capillary attraction, while the sponge absorbs the liquid from the bark and distributes it to the loof, which being very porous permits the air or gas to flow therethrough and saturates it with vapor from the liquid hydrocarbon. 70

K represents a pipe for filling the storage-tank C, having at its top a screw-threaded cup k, in which fits a screw-threaded plug L, made air-tight by means of a soft-metal or fibrous gasket M.

N represents a tube connected with the storage-tank C, closed at its top and having a sight-glass n mounted over a slot in its side.

O represents a float having a rod o secured thereto and mounted in tube N to indicate the quantity of liquid hydrocarbon contained in the storage-tank C. 85

The two compartments C and D are connected by means of pipes P and Q, provided with valves or cocks p and q, respectively, said pipes being vertically arranged relative to one another, the upper pipe P admitting air or gas to the storage-tank C to permit the liquid hydrocarbon to flow through the pipe Q, it being understood that when the liquid hydrocarbon in compartment D rises above 90

the opening to pipe P it forms a seal to said pipe and prevents air or gas flowing into the compartment C; but when the level of the liquid hydrocarbon in compartment D falls 5 below the opening to said pipe the air or gas will pass into compartment C and the liquid hydrocarbon will again flow into compartment D through pipe Q until the liquid covers the opening to pipe P.

10 R represents a draw-off cock in the bottom of the tank for emptying it when desired.

In the modification shown in Fig. 6 the partitions are shown to be curved, while in that shown in Fig. 7 the tank is divided into two 15 mixing-chambers, having staggered partitions in each with common feed and exhaust pipes.

The operation of my invention will be understood to be as follows: The storage-tank 20 C is first filled through pipe K and then the pipes p and q opened to permit the liquid hydrocarbon to flow into compartment D. The strips of redwood-bark H will then absorb the hydrocarbon and saturate the sponge I 25 and vegetable fiber J. The gas or air is then admitted through pipe F, which after passing between partitions E and the filling of redwood-bark, sponge, and loaf or other vegetable fiber becomes thoroughly saturated with 30 hydrocarbon vapor and passes out through pipe G, enriched in illuminating and heating elements.

I have described the filling between the partitions E to consist of three elements—red- 35 wood-bark, sponge, and vegetable fiber, such as loaf; but any one of these fillings may be used to the exclusion of the other two or any two may be used without the third, if desired. The construction of the apparatus 40 may also be changed in non-essential particulars, if desired, without departing from the spirit of my invention.

Having thus described my invention, what I claim is—

45 1. In a gas or air enriching machine, a tank adapted to contain a carbureting fluid pro-

vided with gas inlet and exhaust ports, and strips of redwood-bark in the tank intermediate said inlet and exhaust ports extending down below the normal level of the liquid, substantially as shown and described. 50

2. In a gas or air enriching machine, a tank adapted to contain a carbureting fluid provided with gas inlet and exhaust ports, and vegetable sponge or loaf in the tank intermediate 55 said inlet and exhaust ports extending down below the normal level of the liquid, substantially as shown and described.

3. In a gas or air enriching machine, a tank provided with gas inlet and exhaust ports, 60 and strips of redwood-bark, pieces of sponge and pieces of loaf in the tank intermediate said inlet and exhaust ports, substantially as shown as described.

4. In a gas or air enriching machine, a tank 65 provided with gas inlet and exhaust ports, a plurality of partitions intermediate said ports and having staggered openings therebetween, strips of redwood-bark arranged next to said partitions, and pieces of sponge and loaf be- 70 tween said strips of bark, substantially as shown and described.

5. In a gas or air enriching machine, a tank divided into two compartments connected by valved pipes arranged on different horizontal 75 planes, a filling-pipe and gage connected with one compartment, gas inlet and exhaust ports in the other compartment, a plurality of partitions intermediate said ports and having staggered openings therebetween, strips of 80 redwood-bark arranged next to said partitions, and pieces of sponge and of loaf between said strips of bark, substantially as shown and described.

In testimony whereof I have hereunto affixed 85 my signature in presence of two subscribing witnesses.

CHAS. S. KLINE.
